(57) **CLAIM**

The ornamental design for the bucket, as shown and described.

DESCRIPTION

FIG. 1 is a perspective view of the bucket;
FIG. 2 is a top plan view of the bucket;
FIG. 3 is a right side elevation view of the bucket;
FIG. 4 is a left side elevation view of the bucket;
FIG. 5 is a first end view of the bucket;
FIG. 6 is the view of the end opposite the first end view of the bucket; and,
FIG. 7 is a bottom plan view of the bucket.
The broken lines shown in the figures are for illustrative purposes only and form no part of the claimed design.
